DESCRIPTION

(62) Division of application No. 29/298,787, filed on Jun. 24, 2004, now Pat. No. Des. 513,118.

FIG. 1 is a side perspective view of an umbrella parasol for patio or beach use showing my new design in condition of use with a curved pole and stand; and,

(51) LOC (8) Cl. 03-03

FIG. 2 is a front perspective view thereof shown in condition of use with an ornamental endcap, partial pole and crank-shaft.

(52) U.S. Cl. D3/5

The broken line showing of an ornamental endcap, pole, stand and crankshaft is for illustrative purposes only and forms no part of the claimed design.
